ELECTRIC HEATER

Lee P. Hynes, Philadelphia, Pa.

Application January 29, 1932, Serial No. 589,735

19 Claims. (Cl. 219—38)

For a detailed description of the present form of my invention, reference may be had to the following specification and to the accompanying drawings forming a part thereof, wherein

- 5 Fig. 1 is a side elevation of my heater;
Fig. 2 is a vertical section thereof;
Fig. 3 is a horizontal section thereof;
10 Figs. 4, 5 and 6 are enlargements of the important details;
Fig. 7 shows a modification;
Figs. 8 and 9 show details.
15 My invention relates to an electric heater wherein the heating member consists of flat hollow tubes or cells carrying thin heater elements, so constructed and arranged as to insure a rapid 20 heat transfer with a low gradient of heater temperature, and the presentation of the least active heating surfaces to the erosive action of the fluid current set up by the convection.
25 In my application for patent, Serial No. 379,381, filed July 11, 1930, I have shown a liquid-heating system characterized by the performance of the heating in a separate chamber underneath the main body of the heater. From this underneath 30 heating chamber the liquid, after being heated, is piped up to the top of the main heater, while from the bottom of the said main heater the cooler water flows down to the heating chamber aforesaid there to be reheated and in turn piped up again to the top. I draw off hot water from the said top of the main heater, preferably by an interior pipe which leads from there down along parallel with the up-going pipe aforesaid.

35 My present invention relates to certain improvements on my aforesaid heating system, although not limited thereto. In particular, I construct the electric heater with a series of flat stiffened heater tubes or cells, mounted with their flat sides vertically disposed in the fluid to be heated. Said heater tubes or cells are open to the atmosphere, whereby electric heating elements may be readily inserted into and removed from said stiffened tubes or cells without disturbance of the liquid container into which they 40 project. By this arrangement, the wider vertical surfaces are constantly and so effectively scoured by the fluid currents, that they are kept free of scale and similar deposits of the type commonly given up by water and other fluids while being heated. A further advantage is that any such accumulation of scale and the like is confined to the top, thin edge of the flat tube or cell, at a location where its presence has little or no insulating, or other detrimental effect, because this 45 is the smallest and least active heating area.

These flat stiffened tubes serve as open ended cells, being sealed externally by welding to the wall of their container in the aforesaid chamber, but opening internally to the atmosphere for the reception and removal of the electric heating elements. Other features of my present invention will appear hereinafter.

5 Referring to the drawings, A represents an outer casing separated by insulation from the inside regular heater casing B. The casing B extends below its arched bottom G to form an underneath compartment in which I locate the heating apparatus. This apparatus consists of a cylindrical container S enclosing the flat cells D and E. These cells are shown on a large scale in Figs. 4 and 5 15 and are formed by compressing a round pipe to the flat form shown. These flat cells being exposed internally to atmospheric pressure and externally to the tank pressure, would, if too thinly constructed, soon become closed by the external 20 pressure, which would force their two flat sides into contact with each other. To avoid this vertically disposed stiffening ribs K may be welded on the outside of D and E at intervals, which extend across the vertical sides of D and E. The 25 ribs K also serve to provide extended surfaces for conducting heat to the fluid, and further, to reduce the gradient of the heater temperature. Said ribs may be omitted without departing from the 30 spirit of the invention, it being preferred to employ them only when the metal, of which the flat cells are constructed, is too thin to normally stand the pressures, or where it is desirable to increase the heating surface and reduce the temperature 35 gradient. It should be noted that these ribs have 40 their fluid heating surfaces in a vertical line, so as to be washed by fluid currents, and that they present their smallest surface in the line of precipitation of sediment, in the same manner that the hollow tubular members do. Then on the respective ends of D and E, I weld discs O and P, which close respectively the two ends of the cylindrical container S but are perforated by windows J, J, that receive the ends of the flat tubes or 45 cells D and E which are welded to the discs at the windows therein through which they pass. The discs O and P are then welded at their peripheries to the respective ends of the cylindrical container S. This leaves the two ends of D and E open to the atmosphere and flush with the outer faces of discs O and P. In the upper side of said container S a hole is cut and around this hole, but spaced from it, is welded to the outside of S a short upright tube V, and into said hole is welded 50 a downwardly projecting tube V¹, as is best shown 55

in Fig. 5, which reaches nearly to the bottom of container S.

This provides a unitary heating structure, composed of the open-ended flat tubes D and E, the 5 stiffening ribs K thereon, the discs O and P, the cylinder S, the tube V standing upright above said cylinder, and the tube V¹ projecting down into said cylinder. This structure is placed in the said 10 space underneath the tank casing B, with the open ends of D and E in line with doors F, F formed in the outside casing A and in the downward projecting wall of tank B below the arched bottom C. The upright tube V projects up into the bottom of 15 the tank B being screw threaded into a ring G that is welded in the bottom plate C of said tank.

Thus the lower end of said casing B terminates in a separate heater consisting of the transverse cylinder S, inside of which cylinder are the open-ended flat cells D and E, with their flat sides 20 vertical, while the interior of said cylinder S, outside of said tubes D and E and the ribs thereon, communicates at its bottom with the interior of casing B through the aforesaid downwardly projecting tube V¹.

As a result of this construction the cooler water 25 in the lower part of tank B can flow down, through tube V, into the bottom of the space within cylinder S and surround, in said space, the outside of the ribbed flat cells D and E containing the removable heater elements. This water in cylinder 30 S will become heated and, when so heated, I pipe it off to the top of tank B by means of a pipe N which passes up, from said space within cylinder S, through the upright tube V, but is located eccentrically therein, to the top of the tank. This pipe N establishes a circulation route, the heated water flowing constantly up from cylinder S by 35 said pipe N to the top of the tank. The water in the tank will continue to gain in heat until the 40 thermostat acts and shuts off the flow of electric current in the heating coils.

While the hotter water from the top of the tank might be drawn off therefrom directly for service 45 purposes, I prefer to draw it off by means of an interior pipe R which leads from the top part of the tank down through the aforesaid upright tube V and the downwardly-extending tube V¹ to and thence through the bottom of cylinder S, to the outside faucet pipe W below the cylinder. 50 This passage of the pipe R through the bottom of cylinder S occasions the use of a screw connection, the pipe R being screwed into the top of a ring or nipple T, and into the bottom of ring T is screwed the faucet pipe W, while the ring 55 T is itself screwed into a ring M welded to the bottom of cylinder S. At most of the other joints in my construction I am able to weld the parts together and make them practically integral.

The electric heaters which I employ are shown 60 in Fig. 4 inside of the flattened tubes D and E. They are flat, rectangular, metal-clad pieces, say 2½ inches wide, $\frac{1}{8}$ of an inch thick and 14 inches long. Inside of the metal skin are the resistance 65 wires, embedded in fire and water-proof insulation, and the outside terminals are shown at one end at X and Y. These pieces can be readily slipped into or out of the open ends of the aforesaid flat cells D and E through the door F in the outside case A and the wall of casing B and 70 the door closed behind them. Above this door F in casing A is a smaller door Q in the outside casing A through which a thermostat Z may be inserted and lie inside the closed door Q against the inner casing B and within the intervening 75 layer of insulation. A suitable framing U may

encircle these doors on the outside of casing A to carry the door hinges and give finish to the appearance of that casing.

The above-described electric heater, consisting of flat, reinforced, open-ended cells exposed on one side to the water or other liquid, and on the other, atmospheric, side capable of receiving removable heater cells may be utilized in other ways than that above described. For example, 5 in Fig. 7 I have shown two groups of such coils 10 welded directly into the wall of a tank B at different levels, instead of being placed inside a separate container S that communicates with the tank.

What I claim as new and desire to secure by 15 Letters Patent is:

1. An electric heater comprising a tank, an external chamber located below said tank, a flat cell supported by the wall of said chamber and having an outer end open to the atmosphere, said cell 20 being extended horizontally into said chamber with its side surfaces disposed vertically, the cell being so constructed and arranged that convection current flow within said chamber will travel transversely of and approximately parallel with 25 the wider surfaces of said cell and will expose to the erosive action of such current flow a maximum heating area for a minimum distance of current travel, whereby deposited accumulation is confined to a narrow edge of each pocket, and an electric heater unit insertible into and removable from said cell through the open end of the latter, said unit having terminals insertible and removable therewith, and means establishing fluid communication between said tank and said 30 chamber.

2. In an electric fluid heater, a container, a flat cell sealed inside of the container and open at one end to the atmosphere, said cell being extended horizontally into said chamber with its side surfaces disposed vertically, the cell being so constructed and arranged that convection current flow within said chamber will travel transversely of and approximately parallel with the wider surfaces of said cell and will expose to the erosive 45 action of such current flow a maximum heating area for a minimum distance of current travel, whereby deposited accumulation is confined to a narrow edge of each pocket, and ribs arranged transversely of the flat surfaces of said cell and approximately parallel with said current flow.

3. An electric heater comprising a tank, a cylindrical container below said tank, means constructed and arranged to establish intercommunication between said container and said tank, a flat cell extended into said tank and supported by a wall thereof, said cell having an end open to the atmosphere, said cell being extended horizontally into said chamber with its side surfaces disposed vertically, the cell being so constructed and arranged that convection current flow within said chamber will travel transversely of and approximately parallel with the wider surfaces of said cell and will expose to the erosive action of such current flow a maximum heating area for a minimum distance of current travel, whereby deposited accumulation is confined to a narrow edge of each pocket, and ribs arranged transversely of the flat surfaces of said cell and approximately parallel with said current flow.

4. An electric fluid heater comprising a fluid-receiving chamber, a plurality of thin flat heater pockets each having an open end attached to a wall of said chamber, said pockets being extended horizontally into said chamber and with

their wide surfaces disposed vertically, said pockets being so constructed and arranged that convection current flow within said chamber will travel transversely of and approximately parallel with the wider surfaces of the pockets and will also expose to the erosive action of said currents a maximum heating area for a minimum distance of convection current travel, whereby deposited accumulation is confined to a narrow edge of each pocket, and flat metal-clad heater elements complementary to said pockets and removably inserted therein.

5. An electric fluid heater comprising a chamber having one or more slots in a wall thereof, a corresponding number of thin flat flow-directing heater pockets extended through the respective slots, said pockets being extended horizontally into said chamber with their side surfaces disposed vertically, said pockets being so constructed and arranged as to provide flat parallel flow-directing walls forming fluid swept vertical heating surfaces parallel to the direction of sediment precipitation, the wider surfaces of the pockets providing a maximum heating area for a minimum distance of convection current travel, whereby deposited accumulation is confined to a narrow edge of each pocket, flat complementary heater elements removably inserted into said pockets and removable therefrom through the open ends thereof, means to conduct cool fluid to the level below the pockets, means for conducting heated fluid from the chamber at a level above said pockets, and means for automatically shutting off electric power when the fluid within said chamber reaches a predetermined temperature.

6. An electric fluid heater of the character described comprising a pressure vessel, a heat-retaining enclosure for said vessel, a plurality of flat hollow tubular members extended through the wall of said vessel, and projecting horizontally into the interior thereof with their flat sides vertically arranged, said tubular members being open at their outer ends so as to communicate with the outside atmosphere, said pockets being so constructed and arranged that convection current flow within the pressure vessel will travel transversely of and approximately parallel with the wider surfaces of the pockets and will also expose to the erosive action of said currents a maximum heating area for a minimum distance of convection current travel, close fitting flat parallel walled electric heaters removably inserted into the respective tubular members through the openings in the ends thereof and so positioned that their heat delivering walls are in close proximity to the fluid-washed parallel vertical walls of the tubular members, means for introducing cool fluid below the hollow tubular members, means for removing fluid from above said members, and automatic means for controlling the temperature of the fluid.

7. An electric fluid heater comprising a fluid receiving chamber, a plurality of thin flat heater pockets arranged in vertically spaced relation within said chamber, each of said pockets having an open end attached to a wall of said chamber, said pockets being extended horizontally into said chamber and with their wide surfaces disposed vertically, said pockets being so constructed and arranged that convection current flow within said chamber will travel transversely of and approximately parallel with the wider surfaces of the pockets and will also expose to the erosive action of said currents a maximum heat-

ing area for a minimum distance of convection current travel, whereby deposited accumulation is confined to a narrow edge of each pocket, and flat metal-clad heater elements complementary to said pockets and removably inserted therein.

8. An electrically-heated tank, comprising a container below the tank and communicating therewith, by an upstanding tube, and open-ended heater cell in said container, a pipe extending upward through said tube from the container to the top part of the tank, and a draw-off pipe from the top part of the tank extending through the bottom of said container.

9. An electric heater comprising a tank, a separate container having its lower part in communication with the lower part of the tank, a heater-holding cell in said container having one end open to the atmosphere, a pipe between the top part of the container and the top part of the tank, and a draw-off pipe leading from the top part of the tank through said container to the atmosphere.

10. An electric heater comprising a tank, a separate container outside the tank, an upright tube projecting from the top of said container into the bottom of the tank, a second tube extending from the top of said container to the bottom internal part thereof, a pipe extending from the top part of said container and through the said upright tube to the top part of the tank and means for drawing off hot water from the top part of the tank.

11. An electric water heater tank having horizontal flat heater pockets welded into its shell and vertical reinforcing ribs welded to the pocket walls, said pockets having an external open end to receive flat metal clad heaters, and automatic means to disconnect the power from the heaters when any desired temperature is reached.

12. An electric water heater consisting of a pressure tank, a plurality of flat tubes welded into the tank shell and having an open end permitting the insertion and withdrawal of thin flat heaters, and a flat tube having a series of vertical ribs to reinforce its walls against a collapsing pressure and to increase its heating surface and to permit the upward thermal flow of water.

13. An electric heater comprising a tank, a circulator beneath the tank, flat tubes in the circulator, having an external open end to receive flat metal clad heaters, fins on the outside walls of the flat tubes, a duct to connect the circulator to the tank with a single pressure joint enclosing passages to conduct cool water down from the bottom of the tank to the lower part of the circulator, and other passages to conduct the heated water to the top of the tank from the upper part of the circulator.

14. An electric water heater having a T shaped circulator in the horizontal portion of which are flat removable heaters in flat horizontal pockets having vertical ribs on their exterior walls, and in the vertical portion of which a plurality of conduits for the passage of water in different directions, the vertical portion serving to attach the circulator to the tank with a single pressure joint.

15. A hot liquid storage tank having downwardly extended walls, a connection near the center of the tank bottom, a horizontal cylinder located within the extended tank walls and attached to the tank by a single vertical conduit projecting from its upper side near the middle, the horizontal cylinder containing flat water tight heater pockets with one end open externally

to receive flat metal clad heater strips, and the vertical conduit containing a plurality of passageways for directing the flow of liquid between the tank and the cylinder beneath it, vertical tubes extending from the horizontal cylinder to the top of the tank, and a plurality of pipe connections to the bottom of the horizontal cylinder.

16. An electric storage water heater comprising a cylindrical vertical tank having suspended from its bottom near the central axis, a small horizontal container, the attachment member forming a conduit containing passageways and tubes communicating to different levels in the storage tank and to different levels in the lower container, with electric heating elements mounted within the lower container.

17. An electric heater comprising a storage tank, a heating chamber beneath the tank connected to it by a vertical tube, a passageway within said tube reaching down into the interior of the container, a second passageway within this tube leading upward from the top of the container and electric heating elements within the container.

18. A fluid heater comprising a cylindrical pressure chamber, a plurality of flat hollow heater members extended into said chamber and arranged with their longest dimensions horizontally disposed, and their side surfaces disposed vertically, so as to confine the heat input to localized strata of liquid, said heating members being so constructed and arranged as to provide parallel approximately vertical flat surfaces arranged to direct thermal flow and to avoid deposit of sediment upon the main heating surfaces and to ex-

pose a maximum heating area for a minimum distance of thermal flow of the fluid, thin flat heater elements removably insertible through the open ends of said heater members, an outer insulating jacket for said pressure chamber, said jacket having an enclosure for the terminals of the heating elements externally of said chamber, and means for supplying cool liquid to a level below the heater members and other means for withdrawing liquid from above the level of said heater members.

19. A fluid heater comprising a tank, an insulator enclosure for said tank having chambers therein, a plurality of flat hollow heater members extended into said tank and having open ends communicating with the respective chambers, said pockets being extended horizontally into said chamber and with their wide surfaces disposed vertically, said pockets being so constructed and arranged that convection current flow within said chamber will travel transversely of and approximately parallel with the wider surfaces of the pockets and will also expose to the erosive action of said currents a maximum heating area for a minimum distance of convection current travel, whereby deposited accumulation is confined to a narrow edge of each pocket, flat metal-clad heater elements complemental to said pockets and removably inserted therein, the chambers in the insulation enclosure being constructed and arranged to receive the electrical connections for the heater elements, and closures for said chambers.

LEE P. HYNES. 35
